(57) CLAIM

The ornamental design for a glue dispensing head, as shown and described.

DESCRIPTION

FIG. 1 is a perspective view of a glue dispensing head showing my new design, wherein a removably attached glue bottle and a slotted, wood frame member are shown in broken lines for illustrative purposes only and form no part of the claimed design;

FIG. 2 is a top plan view of the glue dispensing head of FIG. 1 as shown in isolation;

FIG. 3 is a front elevation view thereof, the opposite rear elevation view comprising a substantial mirror image thereof;

FIG. 4 is a bottom plan view thereof;

FIG. 5 is a side elevational view of the left side of FIG. 3; and,

FIG. 6 is a side elevational view of the right side of FIG. 3.
